(57) **CLAIM**

The ornamental design for a fluidic processing workstation, as shown and described.

DESCRIPTION

FIG. 1 is a front isometric view of a fluidic processing workstation;

FIG. 2 is a rear isometric view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a rear elevation view thereof;

FIG. 8 is a front isometric view thereof with an environmental structure;

FIG. 9 is a front isometric view thereof showing bag suspension arms in an alternative position; and,

FIG. 10 is a rear isometric view thereof showing bag suspension arms in an alternative position.

The broken lines of FIG. 8 depict environmental subject matter and form no part of the claimed design, and the remaining broken lines depict portions of the fluidic processing workstation that form no part of the claimed design.
